UNITED STATES PATENT OFFICE

LOUIS J. SAUER, OF OAK PARK, ILLINOIS, ASSIGNOR TO CHARLES H. JOY, SR., OF CHICAGO, ILLINOIS

FEEDING DEVICE FOR DUPLICATING MACHINES

Application filed June 3, 1929. Serial No. 367,946.

My invention relates to feeding devices for duplicating machines, with special reference to that class of machines wherein is provided a flat gelatinized printing surface over which a platen carriage, having a suitable platen roller, is arranged to travel. In this type of machine the paper, or a suitable card is inserted in the carriage and the platen roller impresses the original or the copy sheet on the gelatinized printing surface which receives the impression from the original sheet and transfers it to the copy sheet.

In order that the copy sheet should register accurately with the impression on the printing surface, it is necessary that the card or sheet should be fed into the carriage and under the platen roller and pressed on the printing surface in exactly the same position as the original.

In my invention I have provided a convenient means for accomplishing the desired result and it has for one of its objects the provision of a card or paper aligning and feeding device which will allow the card or paper to be automatically fed under the platen roller and transferred to the printing surface in a position to accurately register with the impression.

Another object is to provide a device which will feed and accurately register cards of various sizes.

A further object is the provision of a feeding device arranged for feeding a plurality of cards of the same or different size and provided with suitable adjustable guides for accurately registering the cards.

Another object is to provide an automatic feeding device which will be operated by the movement of the carriage and which will not interfere with any of the normal movements or operations of the carriage and its associated parts.

Further objects will appear from the detailed description to follow and from the appended claims.

In the drawings:—

Figure 1 is a side elevation of a portion of a hectograph machine embodying my invention, a portion of the carriage being bro-

ken away, the printing position of the carriage and the platen roller being shown in dotted lines;

Fig. 2 is a perspective view of the paper feed mechanism as applied to the carriage;

Fig. 3 is a perspective view of the spring means for controlling the paper feed;

Fig. 4 is a detailed section through one of the adjustable guide members and taken on the line 4—4 of Fig. 2;

Fig. 5 is a perspective view of one of the adjustable guide members; and

Fig. 6 is a perspective view of one of the guide clamping blocks.

Referring now to the drawings in detail, my invention, as illustrated, comprises a hectograph frame 1 supporting the usual gelatinized printing surface 2, as illustrated in Fig. 1, in which I have shown the carriage 3 in its extreme forward position. This carriage is of the usual type and comprises a substantially rectangular frame member 4 slidably mounted on the rod 5 by means of a suitable bearing 6 and arranged for longitudinal movement over the printing surface 2. A platen roller 7 is mounted in suitable bearings on the yoke 8 which is, in turn, pivotally supported in the carriage by means of the bearing rod 9 and is provided with a handle 10 for raising and lowering the platen roller, the platen roller cooperating with the pressure roller 11 in feeding and removing the paper or card in the usual well-known manner.

In Fig. 1, I have illustrated the extreme forward position of the carriage in full lines, and in this position the platen roller is raised away from the printing surface as shown. A movable margin bar 12 is arranged to move automatically from the position shown in dotted lines to that shown by full lines when the platen roller is raised while the carriage is in its extreme forward position and to retreat to the lowered position when the platen roller is lowered.

This margin bar operation is controlled through the movement of the yoke 8 the mechanism not being shown as it forms no part of the present invention.

The paper table or guide plate 13 is se-

cured to the frame 4 by means of the screws 14 and at such an angle that paper or cards placed thereon will slide between the platen roller 7 and the pressure roller 11 and be engaged and definitely located by the margin bar 12. A rod 15 is mounted in the bearings 16 on the back of the printing table and is provided with the L-shaped arms 17 on which is mounted the stop member 18 which extends parallel with and adjacent the lower edge of the paper table 13. This stop member is normally held in the position shown in Fig. 2 and in the dotted lines of Fig. 1 by means of the spring 15a and in this position cards or paper laid on the table 13 will be held thereon. The inturned flange 18a engages the under side of the guide plate 13 to limit the movement of the stop member 18.

20 The depending arm 19 is secured to the shaft 15 and arranged to engage the stop 20 on the frame 1 when the carriage moves to the extreme forward position. As the stop bar 18 is moved away from the edge 25 of the paper table the card or paper is allowed to slide between the rollers and engage the margin bar.

Guide members 21 are slidably mounted on the table 13 and are each provided with 30 a guide flange 22, the downwardly extending portion 23 having the inturned flange 24 thereon. These guide members are arranged to be clamped on the table, in a position to act as guides for any desired size of 35 cards, by means of the thumb screws 25 and the clamping block 26. The block 26 rests against the inturned flange 24 and is clamped against the down turned flange 27 on the table 13, as illustrated in Fig. 4; by 40 this means cards of any desired size may be used or by the use of a plurality of these guides cards of different sizes may be fed into printing position simultaneously.

In operation the platen roller is moved 45 downwardly by means of the handle 10 to engage the printing surface and the carriage moved towards the rear of the machine, as shown by dotted lines in Fig. 1, where it engages a suitable, adjustable 50 stop member 28 which is adjusted to limit the movement of the carriage to a position corresponding to the length of the cards used. With the carriage in this position, the card is placed upon the table 13, where 55 it rests against the stop bar 18, and is held in lateral alignment by means of the guide member flanges 22. The carriage is then moved forward to the position shown in full lines where the card is released through 60 the engagement of the lever 19 with the stop 20.

It will be noted that when the carriage is in the forward position shown in Fig. 1, the cards or paper may be fed directly into the 65 machine by hand in the usual manner, the

automatic feeding mechanism not interfering in any way with the normal operation of the machine.

A considerable saving of time is gained by placing the card on the guide plate when 70 the carriage is at the rear position, as the hand is then free to remove the printed card as it is raised from the printing surface through the forward movement of the carriage, in the usual manner. 75

Having thus described my invention, what I claim and desire to secure by Letters Patent is:

1. An automatic feed for duplicating machines comprising a carriage shiftable over 80 a printing surface, a guide plate on said carriage, means for retaining paper on said guide plate, and means independent of the carriage and cooperating with said retaining means to release the paper through the 85 movement of the carriage.

2. A feeding device for duplicating machines comprising a carriage shiftable back and forth over a printing surface, an inclined guide plate on said carriage to receive 90 a plurality of cards, means for determining the position of the edge of a card with respect to said printing surface, adjustable guide members for adjusting the lateral position of said cards, retaining means for 95 said cards, and means whereby said retaining means is made ineffective by the movement of said carriage.

3. An automatic feed for duplicating machines comprising a carriage shiftable over 100 a printing surface, an inclined guide plate on said carriage, a movable paper stop member on said carriage adjacent the lower edge of said guide plate, means for moving said stop member out of engagement with said paper, and means independent of said carriage for engaging and operating said stop member moving means during the movement of said carriage. 105

4. A paper feed for movable carriage duplicating machines comprising an inclined guide plate on said carriage, a shaft adjacent the back of said guide plate, a paper supporting member adjacent the lower edge of said guide plate and secured to said shaft, means on said shaft and cooperating with means independent of said carriage to hold said supporting member ineffective at the forward position of the carriage and means for moving said paper supporting member into effective position when the carriage is moved from its forward position. 110

5. In a duplicating machine the combination with a frame supporting a printing bed and having a carriage shiftable back and forth over said bed, a platen roller on said carriage, a pressure roller on said carriage for cooperation with said platen roller, an inclined guide plate on said carriage and in alignment with the opening between said 115 120 125 130

rollers when said platen roller is in raised position, a margin bar for registering cards on the printing bed when received from the guide plate, a movable stop member adjacent the lower edge of said guide plate, means for retaining said stop member in effective position to support cards on said guide plate, and means on said frame and independent of said carriage for holding 5 said movable stop in ineffective position when said carriage is in its extreme forward position.

6. In an automatic feed for duplicating machines the combination with a frame supporting a printing bed and having a platen carriage shiftable back and forth over said bed, of an inclined guide plate on said carriage, laterally adjustable guide members on said plate, a paper supporting stop bar adjacent the lower edge of said guide plate and hinged for movement from effective to ineffective position, spring means for retaining said stop bar normally in effective position, and means on said frame for making 10 said stop bar ineffective when the carriage is in its forward position.

7. A guide for paper feed device comprising a guide plate having a depending flange, an adjustable guide member slidably mounted on said guide plate and having a depending flange longer than said guide plate flange and having its edge inturned to substantially the thickness of the guide plate flange, a clamping block engaging said guide plate flange and said inturned edge, and means for clamping all of said parts together.

8. A feeding device for a duplicating machine comprising a carriage shiftable back and forth over a printing surface for applying and removing the paper with respect to said surface, means for determining the position of the edge of the paper with respect to the printing surface, a platen roller mounted on said carriage movable toward and from the printing surface for applying the paper to the printing surface, a handle mounted for movement in a single plane only for controlling the movement of the carriage and platen roller, an inclined paper support on said carriage, releasable retaining means for said carriage for retaining the paper on the support and withholding it from said determining means, and means for automatically releasing said retaining means when the carriage is adjacent its initial position.

9. A feeding device for a duplicating machine comprising a carriage shiftable back and forth over a printing surface for applying and removing the paper with respect to said surface, a platen roller mounted on said carriage movable toward and from the printing surface for applying the paper to the printing surface, a handle mounted for movement in a single plane only for con-

trolling the movement of the carriage and platen roller, an inclined paper support on said carriage, releasable retaining means for said carriage for retaining the paper on the support, means for automatically releasing said retaining means when the carriage is adjacent its initial position, said means comprising a movable member mounted on the carriage, and means mounted on the frame cooperating with the movable means to release the retaining means.

10. A duplicator construction comprising a carriage movable back and forth over a printing surface, an inclined paper support on said carriage, means for determining the position of the edge of the paper with respect to the printing surface, retaining means adjacent the lower edge of the paper support and movably mounted on said carriage, which in one position engages the lower edge of the paper to hold it on the support and in another position releases the paper to permit it to slide downwardly along the support to said determining means prior to applying the paper to the printing surface, and means for automatically moving said retaining means to releasing position at a certain stage of movement of the carriage.

11. A duplicator construction comprising a carriage movable back and forth over a printing surface, an inclined paper support on said carriage, means for determining the position of the edge of the paper with respect to the printing surface, retaining means adjacent the lower edge of the paper support and movably mounted on said carriage, which in one position engages the lower edge of the paper to hold it on the support and in another position releases the paper to permit it to slide downwardly along the support to said determining means prior to applying the paper to the printing surface, and means for automatically moving said retaining means to releasing position at a certain stage of movement of the carriage, said retaining means comprising a stop member movable from above the plane of the paper support to a position below the plane of the paper support.

12. A duplicator construction comprising a carriage movable back and forth over a printing surface, an inclined paper support on said carriage, means for determining the position of the edge of the paper with respect to the printing surface, retaining means adjacent the lower edge of the paper support and movably mounted on said carriage, which in one position engages the lower edge of the paper to hold it on the support and in another position releases the paper to permit it to slide downwardly along the support to said determining means prior to applying the paper to the printing surface, and means for automatically mov-

ing said retaining means to releasing position at a certain stage of movement of the carriage, said retaining means comprising a stop member movable from above the plane of the paper support to a position below the plane of the paper support, and means for mounting said member to move about an axis underneath the paper support.

13. A duplicator construction comprising a carriage movable back and forth over a printing surface, an inclined paper support on said carriage, retaining means adjacent the lower edge of the paper support and movably mounted on said carriage, which in one position engages the lower edge of the paper to hold it on the support and in another position releases the paper to permit it to slide downwardly along the support prior to applying the paper to the printing surface, and means for automatically moving said retaining means to releasing position at a certain stage of movement of the carriage, said retaining means comprising a stop member movable from above the plane of the paper support to a position below the plane of the paper support, and means for mounting said member to move about an axis underneath the paper support, comprising a rock shaft, said automatic means comprising an arm on the rock shaft and an abutment engaged by said arm in the movement of the carriage.

14. In a duplicating machine, a carriage mounted to travel over a printing surface, a platen roller mounted on said carriage for pressing the sheet on the printing surface, a margin bar for engaging the edge of the sheet to position it, a support on which the sheets rest prior to passing underneath the roller, and retaining means for holding the sheet on the support and withholding it from said margin bar movable to releasing position to permit the sheet to pass to said margin bar and underneath the roller.

15. In a duplicating machine, a carriage mounted to travel over a printing surface, a platen roller mounted on said carriage for pressing the sheet on the printing surface, means for determining the position of the edge of the sheet with respect to the printing surface, a support on which the sheets rest prior to passing underneath the roller, and retaining means for holding the sheet on the support and withholding it from said determining means movable to releasing position to permit the sheet to pass to said determining means and underneath the roller.

16. In a duplicating machine, a carriage mounted to travel over a printing surface, a platen roller mounted on said carriage for pressing the sheet on the printing surface, means for determining the position of the

edge of the sheet with respect to the printing surface, a support on which the sheets rest prior to passing underneath the roller, retaining means for holding the sheet on the support and withholding it from said determining means movable to releasing position to permit the sheet to pass to said determining means and underneath the roller, and automatic means for controlling the movement of the retaining means.

17. In a duplicating machine, a carriage mounted to travel over a printing surface, a platen roller mounted on said carriage for pressing the sheet on the printing surface, a support on which the sheets rest prior to passing underneath the roller, retaining means for holding the sheet on the support movable to releasing position to permit the sheet to pass underneath the roller, and automatic means controlled by the travel of the carriage for controlling the movement of the retaining means.

18. In a duplicating machine, a carriage mounted to travel over a printing surface, a platen roller mounted on said carriage for pressing the sheet on the printing surface, means for determining the position of the edge of the sheet with respect to the printing surface, a support on which the sheets rest prior to passing underneath the roller, and retaining means for holding the sheet on the support and withholding it from said determining means movable to releasing position to permit the sheet to pass to said determining means and underneath the roller, said retaining means comprising a stop member movable from above the plane of the paper support to a position below the plane of the paper support.

19. In a duplicating machine, a carriage mounted to travel over a printing surface, a platen roller mounted on said carriage for pressing the sheet on the printing surface, means for determining the position of the edge of the sheet with respect to the printing surface, a support on which the sheets rest prior to passing underneath the roller, retaining means for holding the sheet on the support and withholding it from said determining means movable to releasing position to permit the sheet to pass to said determining means and underneath the roller, said retaining means comprising a stop member movable from above the plane of the paper support to a position below the plane of the paper support, and means for mounting said member to move about an axis underneath the paper support.

20. In a duplicating machine, a carriage mounted to travel over a printing surface, a platen roller mounted on said carriage for pressing the sheet on the printing surface, a support on which the sheets rest prior to passing underneath the roller, retaining means for holding the sheet on the support

movable to releasing position to permit the sheet to pass underneath the roller, said retaining means comprising a stop member movable from above the plane of the paper support to a position below the plane of the paper support, means for mounting said member to move about an axis underneath the paper support, comprising a rock shaft, and automatic means for controlling the movement of the retaining means comprising an arm on the rock shaft and an abutment engaged by said arm in the movement of the carriage.

21. In a duplicating machine, a carriage mounted to travel over a printing surface, a platen roller mounted on said carriage for pressing the sheet on the printing surface, means for determining the position of the edge of the sheet with respect to the printing surface, a support on which the sheets rest prior to passing underneath the roller, and retaining means for holding the sheet on the support and withholding it from said determining means movable to releasing position to permit the sheet to pass to said determining means and underneath the roller, said platen roller being movable toward and from the printing surface.

In witness whereof, I have hereunto subscribed my name.

LOUIS J. SAUER.
